UNITED STATES PATENT OFFICE

98,950

DESIGN FOR A BOX OR SIMILAR CONTAINER

James K. La Trell, Los Angeles, Calif.

Application December 20, 1935, Serial No. 60,207

Term of patent 3½ years

To all whom it may concern:

Be it known that I, James K. La Trell, a citizen of the United States, residing at Los Angeles, in the county of Los Angeles and State of California, have invented a new, original, and ornamental Design for a Box or Similar Container, of which the following is a specification, reference being had to the accompanying drawing, forming part thereof.

Fig. 1 is a side elevational view of a box or similar container showing my new design.

Fig. 2 is an end elevational view, and
Fig. 3 is a vertical cross section taken on the line 3—3 of Fig. 1.

The rear side of the box or container, or the side opposite from that seen in Fig. 1 is plain, and the end of the box or container opposite from the end seen in Fig. 2 is plain.

I claim:

The ornamental design for a box or similar container as shown and described.

JAMES K. LA TRELL.
